UNITED STATES PATENT OFFICE.

JULIUS BOEKEL, OF PHILADELPHIA, PENNSYLVANIA.

THERMOSTAT.

1,094,362.

Specification of Letters Patent. Patented Apr. 21, 1914.

Application filed February 12, 1913. Serial No. 747,911.

To all whom it may concern:

Be it known that I, JULIUS BOEKEL, a citizen of the United States, residing at Philadelphia, in the county of Philadelphia and State of Pennsylvania, have invented 5 certain new and useful Improvements in Thermostats, of which the following is a specification.

This invention relates to thermostats of 10 the mercurial type provided with means for mechanically raising or lowering the level of the mercury by means of a movable plunger locked at any desired point to adjust the circuit closing devices according to the degree 15 of heat at which an indication is desired. My Patent #983,345 discloses a good instance of such a thermostat.

My present improvements relate principally to means for insuring perfect electrical contact at the point where the circuit 20 is closed and preventing corrosion of the surface of the mercury; for preventing overflow of the mercury; for preventing accidental short-circuiting by the contact of 25 certain parts with the operator's finger and for permitting easy access to the contacts, though excluding foreign matter therefrom.

More particularly the said invention consists in a float carrying one of said contacts 30 and provided with means for penetrating below the surface of the mercury, thereby preventing any break in the electrical circuit at the point of contact between the float and the mercury, even if the surface of the 35 latter should be corroded; in providing an insulated guide for an attachment of the float carrying the upper contact within the conducting contact casing; in providing an annular mercury receiving groove in the upper 40 end of the post on which the said casing fits and in additional details of the thermostat, all as hereinafter more particularly set forth and claimed.

In the accompanying drawings: Figure 1 45 represents a front elevation of a thermostat embodying my invention, circuit wires *a* and *b* being connected to their respective posts and of a battery in circuit, the said wires being broken away and the dust door 50 being shown closed; Fig. 2, an enlarged vertical section of the upper part of the same; Fig. 3, a cross-section of Fig. 2, taken just above the insulating annular guide; Fig. 4, a detail perspective view of the movable 55 cylindrical door and the fixed cylindrical casing on which it turns, separated but ar-

ranged in proximity to each other; and Fig. 5, a detail perspective view of the post on which the fixed metallic contact casing is screwed and which forms part of the guide 60 for the float.

The mercury tube or reservoir 1 is of usual construction externally screw-threaded at the top to turn into a recess 7 screw-tapped into the lower end of a cylindrical 65 block 6 of insulating material, which may be considered the body of the thermostat. For the material of this body any suitable insulating material may be employed. Just below the tube-suspending screw-thread 70 above mentioned a collar 2 fits tightly on said tube and is provided with a radial stud or screw-post 3 perforated at 4 to receive a wire which is held by a screw 5. In block 6 a vertical hole or passage 8 is provided 75 for the mercury-adjusting plunger 12, which is locked in any position of vertical adjustment, as in the aforesaid patent, by a screw 11, working through the side of said block which is tapped to receive it. The 80 height of the mercury depends on the degree of immersion of said plunger. The latter is of insulating material to prevent electrical contact with the operator's finger, which has been found to occur when operating the 85 adjusting screw hereinafter described, provided a metallic rod be employed for said plunger, as has been usual hitherto.

The adjusting screw 13 of the upper electric contact of the circuit-making and breaking devices turns in the narrow internally screw-threaded upper neck 17 of a cylindrical metallic casing 18, which is internally screw-threaded at its lower end for turning home on a cylindrical integral upwardly extending broad post 19 of block 6, which post has an internal bore 20 for the float hereinafter described, making it a guide for said float. The neck 17 is provided with a laterally extending stud or screw-post 21 perforated 100 at 22 for the reception of wire *b*, the latter being held by screw 23. A lock nut 24 on adjusting screw 13 bears against the top of said neck, fastening said screw and its contact 25 at any point or degree of adjustment. This contact is preferably of platinum embedded in the lower end of a cylindrical steel downward extension of said screw and extending below the same. It enters a chamber 26 in the upper part of 110 casing 18. Below this chamber in said casing there is a larger chamber 27 forming

at its upper end an annular shoulder 28, against which is fitted an insulating guide ring 29 having an internal metallic bushing 30, for guiding an upwardly extending integral rod 31 of an elongated cylindrical steel float 32 convex at both its ends and having a needle form platinum contact 33 projecting from its lower end. The lower circuit making and breaking contact 34 (preferably of platinum) of the thermostat is embedded in the upper end of rod 31 and extends above the same. The metallic casing 18 is open in front as shown from the top down to a point considerably below the guide ring 29, except when closed by a concentric door or shield 35, fitting on the exterior of said casing and adapted to turn thereon, said door being in the form of a cylinder cut away in part for a length and breadth corresponding to the cut away part of the said fixed casing 18. By turning this door to uncover the front of said casing access may be had to the contacts and proximate parts; by turning the said door to close the same, dust and other foreign matters are excluded, a consideration which has been found important in the practical working of the thermostat. The bore or well 20 hereinbefore described extends vertically down through said post 19 into the main part of the body or block 6 communicating through a small hole 37 with a recess in the bottom of said block, the side wall of which is internally screw-threaded to receive and engage the corresponding externally screw-threaded upper end of mercury tube 1. Said hole receives and guides the lower needle-form mercury penetrating contact 33 of float 32.

40 This thermostat differs from the one described in Patent 983,345 most conspicuously in never breaking electrical contact between the mercury and any other part; both of the circuit making and breaking contacts being metallic. It has been found that under the former plan the surface of the mercury would often become oxidized and the same was to some extent true of the contiguous metallic contact, which would be subjected to greater electrical stress and greater heat by increased resistance at this point, so that the electrical connection between this oxidized surface and the metal above it was not reliable. By interposing the float which rises and falls with the mercury, and not relying on the latter to directly open and close the circuit, this danger is manifestly avoided. But, although this combination greatly lessens the oxidation at the point of liquid and solid contact, some oxidization of the mercury surface is always likely to occur from the normal action of the oxygen in the air and the surface thus oxidized becomes an unreliable conductor. It would of course be fatal to

break the circuit at this point and the absolute reliability of electrical connection there becomes highly important. This is insured by the downward extending needle form contact of the lower end of the float, which is continuously embedded in the mercury, penetrating below the oxidizable surface and insuring constant electrical connection and unbroken current so long as the mercury extends up to (or nearly to) the shoulder 36, a matter which is readily controlled by the plunger 12. In practice the float will usually be held by the mercury above this shoulder to a greater or less degree, but it can in no case descend below said shoulder, as the lower end of the float is much greater in diameter than the lower contact pin 33 and forms a shoulder above it stopped by said shoulder 36. Although the hole 37 will guide this contact while the latter is within it such service is unnecessary as the wall of bore or well 20 fits closely enough to the body of the float to guide, without impeding, it. Usually this closeness of fit will prevent any of the mercury from passing up between these surfaces, but to guard against this loss of mercury from this cause, as well as against inconvenience in the operation of the thermostat I have provided an annular recess 38 in the top of post 19, for receiving any mercury which may be drawn up by said float or forced up around it. The subsequent removal of the mercury from this recess is of course very easy, without detriment to the thermostat. Of course it would be possible to substitute other fluid for mercury in such a thermostat, in which case a float of lighter material than steel would preferably be used, and I do not limit myself to these materials or to any others specifically, being at liberty to substitute any metals or other substances adapted to perform the same functions in such a device; but the instrument as described is practically the best. The general operation thereof is described in the said patent, to which reference is hereby made. The operation of the various improvements now applied for has already been sufficiently explained herein. The circuit is from wire *a* through tube 1 and its mercury to the float and the upper contact, the adjusting screw, the fixed casing, the lateral post and wire *b*. When the two coöperating metallic contacts separate there is no circuit.

120 A stud 38 on the fixed casing 18 prevents the shield or door 35 from turning too far in either direction. The edges of the said door are provided with two notches or recesses 39, one of which will fit on said stud in the closed position of said shield, the other recess 39 similarly fitting on said stud in its open position. The engagement of the stud with either one of these notches will prevent said shield or door from being moved up.

ward out of its proper position, besides limiting its turning movement on the casing.

Having thus described my invention, what I claim as new and desire to secure by Letters Patent is:

1. In a thermostatic device forming part of an electric circuit, a float, in combination with means operated thereby for closing and opening said circuit and a mass of oxidizable conducting liquid under and in contact with said float, the latter being provided with a downwardly extending contact pin of relatively small diameter adapted to penetrate the oxidized surface of the mercury and the lower portion of said float being relatively broad and forming a shoulder above said contact pin.
2. In a thermostatic device forming part of an electric circuit, a float, in combination with means operated thereby for closing and opening said circuit, a mass of oxidizable conducting liquid under and in contact with said float, a contact pin of relatively smaller diameter extending centrally downward therefrom and adapted to penetrate the oxidized surface of the liquid and a fixed part through which said pin works up and down with the motion of the float.
3. In a thermostatic device forming part of an electric circuit, a float, in combination with means operated thereby for closing and opening said circuit, a mass of conducting liquid under and in contact with said float, a fixed body in which the said float moves up and down and a part of which extends under the said float, forming an annular shoulder surrounding a central hole, and a contact pin extending centrally down from said float through said hole and guided therein, said contact pin being adapted to penetrate the oxidized surface of the liquid and the lower portion of said float being of considerably greater diameter than that of said pin, so that the said annular shoulder will serve as a stop therefor.
4. In combination with a cylindrical float, a part in which said float is guided in its upward and downward movement and which is provided with a stop preventing said float from descending below a given point, a conducting liquid below and in contact with said float, circuit closing devices operated by said float, and a downwardly presented contact pin carried by said float and extending below said stop when the float is in its lowest position and adapted to penetrate the oxidized surface of said liquid.
5. In combination with an expansible column of liquid, a float having a needle-form contact at its lower end adapted to penetrate the oxidized surface of said liquid, and provided at its upper end with an extended part carrying a contact, an insulated guide for said extended part, another contact arranged to coöperate therewith in closing the circuit

and a casing surrounding these upper contacts.

6. In combination with a column of electrically conducting liquid expansible by heat and a receptacle therefor, a float rising and falling with the same, circuit closing devices operated by said float, a plunger adjustable in said liquid to raise or lower it, a contact pin extending down from said float and a stop under said float for limiting its downward movement, the lower end of said float being of considerably greater diameter than that of said contact pin.

7. A thermostat body and depending mercury tube, in combination with a post raised on said body, externally screw-threaded and internally bored, a casing screwed on said post, a float movable up and down in said bore and electrical circuit closing contacts, one of which is carried by said float, the said bore being extended down through the body and having a shoulder at its lower end, but communicating with the mercury in said tube and fitting the float so as to guide without impeding the same.

8. In combination with a mercury-containing tube, an insulating block provided with a recess for receiving the end thereof, a passage extending through said block to said recess, a bore or well extending down through said block and having a shoulder at its lower end, but communicating with said tube and a raised post containing the upper part of said bore or well and externally screw-threaded, a plunger adjustable longitudinally through said passage, a contact carrying float movable in said bore or well and guided thereby, a casing screwed on said post and a contact mounted in said casing to coöperate with the contact thus carried.

9. In combination with the circuit-closing contacts of a thermostat and a float and expansible mass of liquid operating them, a fixed casing protecting said contacts but having an opening, and a shield or door rotatable on said casing to open or close said opening at will, said casing being provided with a stop arranged for contact with the edge of said shield or door.

10. A float provided with a reduced upper extension carrying a contact and a mass of liquid below and in contact with the same, in combination with a fixed guide for said upper extension, a contact arranged to coöperate with the contact first mentioned, conductors making circuit through such contacts, liquid and float, and a downwardly presented contact pin of relatively small diameter carried by said float, the lower end of the float being of greater diameter, forming a shoulder above said pin and the latter being adapted to penetrate the oxidized surface of the liquid when said float is thus stopped.

11. An electrically conducting float pro-

vided with a reduced upper extension carrying a contact, in combination with a mass of electrically conducting and expansible liquid under and in contact with said float, a 5 fixed insulating guide for such upper extension, a contact arranged to coöperate with the contact first mentioned, conductors making circuit through said contacts, liquid and float, and a stop limiting the downward 10 movement of said float.

12. A float having a reduced upper extension carrying a contact and also provided with a contact extending down from its lower end and of considerably less diameter 15 than that of said float which forms a shoul-

der above it, guides for said extension and said lower contact, means coöperating with said upper contact to close the circuit, and a mass of expansible conducting liquid under and in contact with said float, said lower 20 contact being adapted to penetrate the oxidized surface of said liquid.

In testimony whereof, I have signed my name to this specification in the presence of two subscribing witnesses.

JULIUS BOEKEL.
